ELECTRODE FOR THERAPEUTIC DEVICES

Samuel Ruben, New Rochelle, N. Y.

Application October 28, 1933, Serial No. 695,562

5 Claims. (Cl. 174—89)

This invention relates to electrodes for use in therapeutic devices; specifically for use in connection with the application of high frequency currents to the body.

5 An object is to provide such an electrode which is highly flexible and adaptable for use with any part of the body.

Another object of the invention is to provide such an electrode at a very low cost so that it may 10 be destroyed after a single use or application.

A further object of the invention is to provide such an electrode which is light in weight and which has an adhesive surface so that it may be used with comfort by the patient.

15 Other objects will be apparent from the disclosure and from the drawing in which—

Figure 1 shows an electrode; partly cut away in section and

Figure 2 is an end view of Figure 1.

20 Heretofore, there have been used for such applications, electrodes generally composed of lead sheet or foil which has been bent or formed into shape. In many uses, these electrodes have not been sufficiently flexible or adaptable for 25 the specific purposes required. Furthermore, these electrodes have been limited in the maximum current applicable, due to localized contact and contact resistance.

I have found that by utilizing a flexible and 30 plastic electrode composed of a non-fibrous cellulose sheet which has been rendered highly conductive by plasticization and impregnation with a conductive material such as glycol, glycerol or glycol borate and then rendered adhesive by the 35 addition of a mucilaginous material, that a light weight and universally applicable electrode can be made, capable of allowing the application without skin burns, of currents of greater magnitude than heretofore possible.

40 In order to have minimum internal electrode resistance and to more uniformly distribute the applied current over the entire electrode area, a very thin tin foil sheet is cemented on one side of the conductive cellulose sheet.

45 The flexible sheet material used is preferably a non-fibrous regenerated cellulose such as is popularly designated "cellophane" although other materials such as "Kodapak" or "Protectoid" (cellulose acetate sheets), sheet gelatin or porous 50 membranes may be used in combination with proper plasticizing conductive and adhesive compounds. The practically non-porous "cellophane", however, has given the best results to date.

55 In the preparation of the material, the "cello-

phane" is preferably plasticized by immersion in an aqueous glycol or glycerol compound. It is then passed through and impregnated with a heated conductive compound such as glycol or glycerol borate with which is combined an adhesive such as water soluble glue, gum arabic, gelatin or other mucilaginous material. Additional adhesive may be brushed on after impregnation in which event it combines with the impregnated cellophane and itself becomes conductive. 60

65 The glycol or glycerol borates are preferred as the active conductive materials because of their low vapor pressure and because of their hydroscopic character which tends to maintain the cellulose in plastic conductive condition; however, other compounds such as the chlorides, phosphates, etc., may be substituted.

70 On one side of this flexible conductive "cellophane" sheet is then cemented a very thin metal foil, preferably tin foil of a thickness of approximately 0.00025". The "cellophane" itself is preferably about 0.001" thick, and its adhesive surface affords a good cement for the foil.

75 This combination of conductive plastic material and adhesive, allows the electrode to be placed on any part of the body and affords an intimate contact with the skin, thus allowing a minimum contact resistance drop and maximum distribution of current over the entire contacting area. The adhesive character of the material is such 85 that the electrode weight is easily sustained and intimate contact during treatment is obtained without the use of binding straps or other commonly used accessories.

80 In Figure 1 of the drawing, tin foil (1) is cemented on impregnated plasticized cellophane (2) the adhesive surface of which (3) makes contact with the body of the patient (not shown).

85 In Figure 2, like numbers indicate like parts.

What I claim as new and desire to secure by 90 Letters Patent, is

1. A flexible surface electrode for therapeutic purposes comprising an electrically conductive non-fibrous organic sheet plasticized with a material chosen from the glycol and glycerol compounds, said sheet being adapted to be directly applied to the human body, and a metal backing conductively cemented on said sheet. 100

2. A flexible surface electrode for therapeutic purposes comprising an electrically conductive non-fibrous organic sheet plasticized with a material chosen from the glycol and glycerol borate compounds, said sheet being adapted to be directly applied to the human body, and a metal backing cemented on said sheet. 105

3. A flexible surface electrode for therapeutic purposes comprising an electrically conductive non-fibrous organic sheet plasticized with a material chosen from the mucilaginous glycol and 5 glycerol compounds, said sheet being adapted to be directly applied to the human body, and a metal backing conductively cemented on said sheet.
4. A flexible surface electrode for therapeutic 10 purposes comprising an electrically conductive non-fibrous cellulose sheet plasticized with a material chosen from the glycol and glycerol com-
- ounds, said sheet being adapted to be directly applied to the human body, and a metal backing conductively cemented on said sheet.
5. A flexible electrode for therapeutic purposes comprising an electrolyte impregnated membrane sheet material having a metal foil backing conductively cemented to one surface thereof and having on its other surface a water soluble mucilaginous adhesive adapted to be directly applied to the human body. 80 85
